UPHOLSTERING FURNITURE

David T. Owen, Cleveland, Ohio, assignor to
David T. Owen, Jr., Cleveland, Ohio

Application June 22, 1937, Serial No. 149,739

7 Claims. (Cl. 155—179)

My invention relates to improvements in upholstering furniture, and more particularly chairs, davenport and the like in which curved frames and cushioning springs are employed.

5 One of the principal objects of the invention is to provide means for preventing the distortion of the cushioning springs during upholstering operations.

Another object of the invention is to provide a 10 preformed relatively stiff flexible reinforcing hollow body which will conform to the curved shape of a chair frame or the like to be upholstered and thus obviate the necessity for using skilled workers and much expensive stuffing material.

15 Other objects and advantages of the invention will be understood as the specification is considered in connection with the accompanying drawings in which:

Figure 1 is a perspective view of an upholstered 20 chair partly broken away to show the application of the present invention;

Figure 2 is a section through a chair embodying the present invention;

Figure 3 is an enlarged fragmentary sectional 25 view showing the upholstery form of Figure 2 provided with an auxiliary bracing member;

Figure 4 is a plan view of the upholstery form shown in Figure 1, 2 and 3;

Figure 5 is a section on the line 5—5 of Figure 4;

Figure 6 is a perspective view of the upholstering form shown in Figure 4;

Figure 7 is a front elevation of the brace member employed in the modified upholstery form 30 shown in Figure 9;

Figure 8 is an end view of Figure 7; and

Figures 9 and 10 are perspective views of modified forms of my invention.

Referring more particularly to the drawings 1 35 denotes a chair having a curved substantially U-shaped back frame 2 of conventional form and construction. Secured to the inner face of the back frame 2 are a plurality of wide interwoven fabric strips or webbing 3 which serve as a support for the inner ends of cushion coil springs 4, the outer ends of the springs bearing against a covering of burlap 5. The outer face of the frame 2 is covered by a fabric backing member or sheet 6, preferably of more expensive material than the webbing 3 is made.

The springs 4 are tied together and to the curved top and curved side portions 7 and 8 respectively of the frame 2 and also to the straight cross piece 9 by means of longitudinal and transverse cords 10, in a conventional manner. As previously stated the forward ends of the springs are covered by a sheet or layer 11 of burlap, and upon the layer 11 is a layer 12 of stuffing such as cotton, or the like. A finished upholstering 40 layer 13 of fabric is placed over the cotton and

burlap layers and the whole secured to the frame.

Heretofore it has been the practice to produce the desired curvature, by filling the space between burlap 11 and the finished upholstering fabric layer 13, with toe moss or fiber and the like. However, workmen found it very difficult to produce symmetrical lines, particularly on a border such as the frame 2, and in consequence highly paid skilled workmen are required to do the work. 10 Moreover, the placing and shaping of the stuffing material according to this method has made it practically impossible to avoid spring distortion, due to the fact that when the stuffing material was placed on top of the burlap 11, and pressed 15 into place during the stretching and attachment of the outer finishing layer 13, the cords 10 were forced inwardly and the springs 4 drawn downwardly and out of shape.

According to the present invention I provide a 20 hollow form 14, preferably of relatively stiff but flexible card or paste board, which is suitably secured to the top edge of the frame 2. This form is made from a blank not shown, in which uniformly spaced parallel slots 16 are cut thus 25 forming a plurality of tongues 17, extending from the upper uncut edge or body portion 18 thereof. The tongues are bent as at 19 and 23 to form the inwardly and downwardly extending end attachment and supporting portions 21 and 22 respectively, and the forward edge of the body 18 of the blank as well as that portion of the tongues 17 extending between the body and the bend 19 are curved outwardly and downwardly to form 30 arcuate portions 23. The extremities of the tongues are finally bent rearwardly, as at 24, to provide attachment flanges 25 which engage and underlie the rear or outer edge of the body portion 18.

When the hollow form is in place the flanges 40 25 engage the outer edge of the curved top and side portions of the frame 2, and the portions 22 of the tongues engage the front face thereof. Tacks 15 passing through the body portion 18 and the flanges 25 securely fasten these parts together and to the frame 2, the slots 16, permitting of the hollow form accommodating itself or being bent by the upholsterer to any radius or curvature of frame. The forms 14 are preferably preformed by the manufacturer, as best 45 shown in Figure 4, but for convenience in shipping they may be formed from blanks by the upholsterer, the blanks being scored at 19, 20 and 24 to facilitate this operation.

In practice the webbing 3 is first secured to 50 the frame by tacks 26 and the hollow form 14 is then tacked in place, as indicated in Figure 3. The springs 4 are now assembled and the cords 10 are stretched and attached to the rear of the frame 2, by means of tacks 27, it being noted 55 60

that the ends of both the longitudinally and transversely extending cords pass over the outer edge of the frame. It should also be noted that cords 10 pass over the curved or arcuate portions 5 23 of the tongues 17 and thence around the edge of the frame to the back thereof.

After the cords 10 are stretched and secured to the frame thus securely holding the springs in place and against distortion, the burlap 11 is 10 stretched over the springs 4, cords 10 and the hollow frame and its edges secured to the back of the frame as by tacking or the like. As the hollow body 14 bears all the stress exerted by or upon the cords 10 and burlap layer 11, the springs 15 are not pulled out of true when the cords and burlap are stretched over the hollow body in applying or assembling these parts. Furthermore when the intermediate layer of cotton 12 is superposed on the burlap 11 and the upholstering 20 layer of fabric 13 is stretched, and its edges tacked to the frame in an obvious manner, the springs will remain undistorted, as distinguished from prior constructions, in which the ends of the spring cords do not pass over a supporting 25 member such as hollow body 14. The use of hollow body 14, in addition to simplifying the upholstering operation by preforming the curved border, effects great saving in the cost of labor and makes unnecessary the use of large quantities 30 of stuffing material.

In the modification illustrated in Figures 7, 8 and 9 the hollow body or preforming member 14' is made in two parts. Thus, a member 28 of substantially U-shape and formed of cardboard 35 or the like is bent at 42 to provide a main body portion 29 and arms or branches 30. Integral wings 31 projecting from the rear side edges of the arms 30 are secured to the frame by tacks or similar fasteners 32. A curved arcuate member 33 secured to the outer edge of the frame 40 by tacks 34, or other suitable fasteners, bears against the forward curved edge 43 of the branches 30 and is supported thereby. This member 33 functions in the same manner as the arcuate part 23 of the preferred hollow body 45 member 14, and is slotted at intervals as at 35 to provide the tongues 41 and to permit of the hollow two part form accommodating itself to any radius or curvature of frame. It will be 50 understood that there will be one unit 28 for each tongue 41.

In some instances particularly where the arcuate member is used on small chairs and the like, and consequently of small dimensions, the 55 reinforcing member 28 may be omitted.

A further modification is shown in Figure 10 of the drawings. In this form a curved arcuate preferably cardboard member 36 has its outer edge tacked to the outer edge of the frame 2 as 60 at 37. At intervals throughout the length of the member 36, the material is cut away along three sides to provide hinged supporting and bracing portions 38, which are swung inwardly or rearwardly through the openings 39 thus formed 65 until their free side edges 40 engage the front face of the frame. These hinged members or portions 38 when swung rearwardly or inwardly have the same radius as the radius of the border and brace the arcuate member 36 in an obvious manner. They also obviate the necessity of using a 70 separate part such as the V-shaped member 28 of Figure 9 modification.

In Figure 3 a centrally disposed supporting member or web 44 is employed to support the

curved portion 23 of the hollow form 14. Thus one end of the web 44 seats at the point of juncture between the portions 21 and 22 of the form, and the other end is formed with an offset 5 45 which bears against the under side of the curved portion 23 and supports the latter. This additional supporting web is particularly desirable with high moldings or forms.

Having thus described my invention, what I 10 claim is:

1. A form for the back frames of overstuffed chairs and the like, comprising two straight walls and a curved wall and slots in one straight wall and the curved wall, and means for securing said curved wall to one of said straight walls and to 15 the back frame.

2. A form for curved back frames, comprising a member made from a sheet of relatively stiff material slotted longitudinally to provide a plurality of tongues, said tongues being curved forwardly and downwardly forming arcuate portions, and bent inwardly and thence upwardly to provide straight brace portions and straight attachment portions, said attachment portions having flanges underlying the rear edge of the 20 said sheet and means for securing said flanges and said rear edge portion to the outer edge of 25 the back frame.

3. A form for the back frames of chairs and the like, comprising a slotted sheet of relatively 30 stiff flexible material, said sheet having curved outwardly and downwardly and inwardly and thence upwardly bent portions providing a hollow body said slots extending transversely of the inwardly and upwardly bent portions, the upper 35 inner edge of said sheet and said upwardly bent portions being adapted to be secured to a chair frame.

4. A form for overstuffed chair backs, comprising a sheet having a body portion and plurality of spaced tongues, said body portion and a portion of said tongues being arcuately curved, 40 said tongues having upwardly extending straight attachment portions terminating in attachment flanges, and integral straight supporting and reinforcing portions between said arcuate portions and said attachment portions.

5. A form for overstuffed chair backs, comprising a sheet having a body portion and plurality of spaced tongues, said body portion and a portion of said tongues being arcuately curved, 50 said tongues having upwardly extending straight attachment portions terminating in attachment flanges, and integral straight supporting and reinforcing portions between said arcuate portions and said attachment portions, the said body portion and the flanges being in superposed relation to each other.

6. An elongated unitary preformed flexible form for the border of an upholstered frame, said form having a curved portion, means for attaching one end of the curved portion to the frame, means adapting said form to be bent to arcuate shape and a web brace support for the other end of said curved portion.

7. A premolded form having an elongated unitary body provided with a transversely curved portion adapted to be attached at one end to an upholstered back frame, said form being flexible to permit of the same being bent to arcuate 65 form, and web members extending between the frame and curved portion for supporting said curved portion.

DAVID T. OWEN.
